UNITED STATES PATENT OFFICE

2,441,326

CIGARETTE CASE WITH FLEXIBLE TONGUE

Rolla E. Mudd, Stronghurst, Ill.

Application March 26, 1945, Serial No. 584,909

1 Claim. (Cl. 206—41)

1

My present invention, in its broad aspect, has to do with improvements in cigarette cases, and more particularly, it is my purpose to provide a flexible package holding tongue for use with cigarette cases having ordinary strap or bar hinge connections between the body and the lid whereby bending of a part of the hinge connection about the butt of my tongue will hold the tongue in operative connection with the case, and wherein the tongue is inherently flexible and operable to permit a pack of cigarettes to assume a convenient position for removal of the individual cigarettes, but which will not accidentally release the pack. My invention is characterized by extreme simplicity, sturdiness and practicability, and may be manufactured and sold at a relatively small price.

Other and equally important objects and advantages of my invention will be apparent from the following detailed description and drawings, but it is to be understood that changes in form, size, shape, construction, materials, and arrangement of parts may be made without departing from my broad inventive concept or the scope of the appended claim.

In the drawings wherein I have illustrated a preferred form of my invention:

Figure 1 is a longitudinal section with the cigarette case in open position;

Figure 2 is a top plan view;

Figure 3 is a transverse section with the cigarette case closed;

Figure 4 is a transverse section with the case partly open to remove a cigarette;

Figure 5 is a section on the line 5—5 of Figure 3;

Figure 6 is a fragmentary perspective view of the attaching clip on the butt of my tongue;

Figure 7 is a perspective view of my tongue;

Figure 8 is a section through the cigarette case hinge showing my tongue connected thereto; and

Figure 9 is another section through the hinge.

In the drawings wherein like characters of reference are used to designate like or similar parts throughout the several views:

The numeral 1 designates the body of my cigarette case which may be formed of any suitable material, such for instance as thin metal, and 2 is the top. The top is flanged in the usual man-

2

ner to fit over the upper edge of the body when closed as in Figure 3, and cooperating outstruck lips 3 and 4 are provided to latch the top in closed position so that pressure by the thumb or the like will disengage lips 3 and 4 to open the case, as shown in Figures 1, 2 and 4.

The hinge connections 5 and 6 between the top and body of the cigarette case are conventional strap or bar hinges, between which the edges of 10 the case form webs 7 having a lip 8. The edges or webs are bent inwardly as at 9 for a part of their length as shown in Figures 2 and 7.

My tongue for retaining cigarette packages includes a flexible part 10 extending about half 15 the width of the cigarette case, as shown in Figures 1 and 2, and a butt 11 formed by bending the tongue downwardly and upwardly upon itself as at 12. The end of the butt is bent over to form an attaching flange 13 and the bight between the butt and the flange is formed with a 20 slot 14 to receive the lip 8; the lip 8 is bent over on the flange to hold the tongue in position with the butt bearing against the back wall 15 of the body 1 and the tongue extending out at a slight 25 angle as shown in Figure 1.

In operation, a package of cigarettes A is inserted under the tongue after being partially or fully opened to dispense cigarettes. The tongue holds the package in place against accidental 30 disengagement, but when the case is partly opened and reversed with the top extending downwardly as shown in Figure 4 and shaken, the package takes a slight angular position to discharge one or more cigarettes B as required.

35 From the foregoing, it is believed that the operation and advantages of my invention will be apparent, but it is again emphasized that interpretation of the scope of my invention should only be conclusive when made in the light of the 40 subjoined claim.

I claim:

A cigarette case comprising a body portion having an upstanding peripheral flange, a top hingedly connected to the flange of said body portion, latch means on said body portion formed to be flexed to engage and disengage the same, a preformed flexible plate member detachably mounted on the flange, said mounting means being formed having one end of the plate bent 45 upon itself to form an S-shaped clamp which

engages the flange of the body portion, the plate joining the S-shaped portion substantially in the plane of the free edge of the flange and normally extending outwardly at an angle thereto and adapted to be engaged by said top when said top is in closed position to be moved into parallel relation with said body portion.
